UNITED STATES PATENT OFFICE.

JOSEPH H. WITTMANN, OF KANSAS CITY, MISSOURI.

SUSPENDED COT.

1,278,276.

Specification of Letters Patent. Patented Sept. 10, 1918.

Application filed March 27, 1916. Serial No. 86,974.

To all whom it may concern:

Be it known that I, JOSEPH H. WITTMANN, a citizen of the United States, residing at Kansas City, in the county of Jackson, 5 son and State of Missouri, have invented certain new and useful Improvements in Suspended Cots; and I do declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

My invention relates to a folding bed or cot, and more particularly to a bed for use by tourists or as an emergency bed for residences or hotels; the principal object of 20 the invention being to provide a device of this character which may be completely suspended from a single vertical support, such as the side of a vehicle, the wall of a building, a tree, or the like, or from the 25 single support and from the ground.

In accomplishing this and other objects of the invention, I have provided improved details of structure, the preferred form of which is illustrated in the accompanying 30 drawing, wherein:—

Figure 1 is a perspective view of a suspended bed constructed according to my invention, and illustrating its mounting on a single wall support.

Referring more in detail to the drawings:—

1—2 designate the inner and outer end bars of the bed, and 3, canvas or the like, which connects the end bars and forms the 40 carrying body.

Fixed to the inner end bar 1 are hooks 4, which are adapted for taking into eye-bolts, or the like 5, on a wall or other vertical support 6 to carry the inner end of the bed 45 when the latter is erected and which are substantially S shaped to hold the bar against vertical displacement as well as support the inner end of the bed. If preferred, the hook may be fixed to the wall and the 50 screw eyes on the bar.

Also fixed to the rear end bar are spreader arms 7, which are more than half the length of the bed, and fixed to the opposite end bar 2, are tension bars 10, that are adapted 55 for engagement by the inner ends of the

spreader arms at an angle of ninety (90) degrees or more to afford a compound leverage support for the outer end of the bed, and induce an opening fulcrum action of the tension bar and spreader arms that 60 tends to spread the bars and arms thereby stretching the flexible bed body when weight is placed on the body.

Each tension bar 10 is preferably provided with a plurality of sockets 18 in its 65 under edge, that are adapted for receiving a latch 17 on the corresponding spreader arm to provide adjustment for the bed, and to permit compensation for stretch of the 70 canvas body by locating the latch in proper sockets.

The bed is usually provided with two spreader arms and two tension bars, one of the arms being located at each inner corner of the bed and one of the bars at each outer 75 corner thereof in order to afford the support at the longitudinal edges of the bed. It is apparent, however, that for an exceptionally wide bed, the arms and bars and their connecting parts may be duplicated 80 as often as may be necessary to provide substantial support, or a single arm and bar may be used for a single bed.

In order to suspend the bed at the outer end, I provide the tension bars 10 with 85 hanger cables 12, the lower ends of which are connected with the free ends of the bars 10 and the upper ends of which are supported from hooks, or the like 13, on the supporting wall 6; the upper ends of the 90 cables being preferably provided with links 14, any one of which may take over a hook 13 in order to provide further adjustability 95 of the support and compensation for stretch of the body material.

As there is considerable strain on the spreader arms 7 when there is weight on the bed, that might tend to buckle the arms, I preferably provide each cable 12 with a bifurcated lower end and locate the divided 100 strands 15—15' on opposite sides of the arm to hold the latter against buckling.

In order to hold each spreader arm to its tension bar, I provide the arm with a link 17, which is adapted to take into a 105 notch 18 in the under edge of the tension bar, and in order to lock the spreader arms to their relative tension bars, I provide each arm with a link 20, which is adapted for taking into one of a number of notches 21 110

in the under edge of the tension bar, and when preferred can be provided with a latch 22.

In the drawings I have illustrated what 5 may be termed a double bed, comprising the two sets of spreader arms and tension bars, with the tension bars supported by the cables from the wall 6 at points above the eye-bolts.

10 When a bed constructed as described is not in use it may be collapsed and folded into a relatively small space, as the flexibility of the canvas or other material will permit the spreader arms and tension bars 15 to fold onto each other.

When the bed is to be erected, assuming that the supporting wall is provided with the eye-bolts 5 and the hooks 13, the hooks on the inner supporting bar are located in 20 the eye-bolts, the cable hangers supported from the hooks 13 and the lower ends of the spreader arms 7, seated upon the bars 10; the arrangement being such that the bed will be supported in a horizontal plane. 25 With the bed so arranged the inner end is supported directly from the wall and the outer end from the same wall but from a higher elevation, because of the connection of the outer end of the bed with the hanger 30 cables through the tension bars, and by reason of the abutment of the tension bars against the spreader arms, the compound leverage tending to stretch the canvas when a weight is placed on the bed, because of 35 the tendency of the tension bars to fulcrum on the ends of the spreader arms.

Any stretch of the canvas may be compensated for by readjustment of the spreader arms in the tension bar sockets and in the 40 link support of the cable on the wall hooks.

Should the bed be intended for a continued use without being taken from its mounting, the lock 20, may be utilized as it effects a substantial connection between the 45 tension bars and the spreader arms, although if the bed is used for touring, or the like, when it is to be taken down after a single night's use, the locks need not be utilized.

If so desired the cables 12 may be dispensed with and the ends of the tension bars supported directly from the ground, as with this arrangement downward movement of the inner ends of the tension bars is resisted as effectually as by the overhead support. In either case the inner end pivots on the standing support and the tension bars on the spreaders so that the inclination of the bed is determined by the point of contact of the tension bars with the spreader arms.

50 Having thus described my invention, what I claim as new therein, and desire to secure by Letters-Patent, is:—

1. A structure of the character described comprising a body, supports having spaced 55 connection with the body, an exerting ten-

sion upon the same, one support being seated upon the other to fulcrum away from the body.

2. A structure of the character described comprising a body, supports having spaced 70 connection with the body, with one support seated on the other to fulcrum away from the body, and means for anchoring the structure.

3. A structure of the character described 75 comprising a body, a primary support connected with the body and extended therebeneath, a secondary support connected with the body and having a fulcrum seat on the first support at an angle of not less than 80 ninety degrees, whereby tension on the support, induced by pressure on the body effects an increase of said angle, and means for anchoring the structure to retain the body in 85 its determined plane.

4. In combination with a flexible bed body, a frame comprising separate members connected with opposite ends of the body and extended therebeneath, with one of the members seated on the other, means for anchoring the frame to an independent support, and means for retaining the seated frame member on its seating member.

5. In combination with a flexible bed body, a frame comprising separate members connected with opposite ends of the body and extended therebeneath, with one of the members adjustably seated on the other, means for anchoring the frame to an independent support, and means for retaining the seated frame on its seating member.

6. In combination with a flexible bed body, a frame comprising separate members connected with opposite ends of the body and extended therebeneath, with one of the members seated on the other, means for anchoring the frame to an independent support, and a latch on one of the frame members for engaging the other to hold the stated member in position thereon.

7. In combination with a flexible bed body, a frame comprising separate members connected with opposite ends of the body and extended therebeneath, with one of the members seated on the other, means for anchoring the frame to an independent support, the seating member having rack teeth on its under face and a latch pivotally connected with the seated member and adapted for adjustable engagement with the rack teeth.

8. In combination with a flexible bed body, a frame comprising separate members connected with opposite ends of the body and extended therebeneath, with one of the members seated on the other, means for anchoring the frame to an independent flexible body connecting said bars, tension and spreader members connected with opposite end bars, with the spreader member seating on the tension member, and hangers con-

nected with the inner end of the tension member and with the inner end bar.

9. In a bed comprising a bed body, inner and outer supporting members connected with opposite ends of said body, means for anchoring one end of the body to an independent support and hangers connected with the free ends of outer supporting member, the outer ends of the inner supporting member seating on the outer supporting member above the hanger connection.

10. In combination with a flexible bed body, a frame comprising separate members connected with opposite ends of the body and extended therebeneath, with one of the members seated on the other, means for anchoring the frame to an independent support, and means for retaining the seated frame member on its seating member.

11. In combination with a flexible bed body, a frame comprising separate members connected with opposite ends of the body and extended therebeneath, with one of the members adjustably seated on the other, means for anchoring the frame to an independent support, and means for retaining the seated frame member on its seating member.

12. In combination with a flexible bed body, a frame comprising separate members connected with opposite ends of the body and extended therebeneath, with one of the members seated on the other, means for anchoring the frame to an independent support, and a latch on one of the frame members for engaging the other to hold the seated member in position thereon.

13. In combination with a flexible bed body, a frame comprising separate members connected with opposite ends of the body and extended therebeneath, with one of the members seated on the other, means for anchoring the frame to an independent support, the seating member having rack teeth on its under face and a latch pivotally connected with the seated member and adapted for adjustable engagement with the rack teeth.

14. In combination with a flexible bed body, a frame comprising separate members

connected with opposite ends of the body and extended therebeneath, with one of the members seated on the other, means for anchoring the frame to an independent support, a latch on one of the frame members 55 for engaging the other to hold the seated member in position thereon, and a lock for supplementing the holding action of said latch.

15. A bed, and tensioning means connected with opposite ends of the bed for supporting both ends of the bed from a single ground contacting vertical support.

16. A bed comprising a flexible body having inner and outer end bars, means on the 65 inner end bar for supporting the same from a wall, a tension bar on the outer end bar, a hanger on the tension bar for supporting the bed from a point above the support for the inner end bar, and means on the inner 70 end bar for engaging said tension bar, to spread the flexible body.

17. A bed comprising inner and outer end bars and a flexible body connecting said bars, tension bars on the outer end bar, spreading 75 arms on the inner end bar removably engaging corresponding tension bars, means for attaching the inner end bar to a supporting body, and hangers connecting the tension bars with the supporting body. 80

18. A bed comprising inner and outer end bars and a flexible body connecting said bars, tension bars on the outer end bar, spreading arms on the inner end bar removably engaging said relative tension bars, means for 85 attaching the inner end bar to a supporting body, hangers connecting the tension bars with the supporting body, and means for locking said spreader arms to corresponding tension bars. 90

19. A bed comprising inner and outer end bars and a flexible connecting body, tension bars on the outer end bars, spreading arms on the inner end bars adapted for removable connection with the tension bars, and hangers having bifurcated portions lying on opposite sides of the spreading arms. 95

In testimony whereof I affix my signature.

JOSEPH H. WITTMANN.
